CLAIM

The ornamental design for an insect aggregator, as shown and described.

DESCRIPTION

FIG. 1 is an isometric view of an insect aggregator;

FIG. 2 is a front elevational view of the insect aggregator of FIG. 1, the rear elevational view being identical to the front elevational view;

FIG. 3 is a right elevational view of the insect aggregator of FIG. 1, the left elevational view being identical to the right elevational view; and,

FIG. 4 is a top plan view of the insect aggregator of FIG. 1, the bottom plan view being identical to the top plan view. The broken lines shown in the drawings indicate structure and features which form no part of the claimed design.
